SHIRT COLLAR CONSTRUCTION

Samuel Burton, Los Angeles, Calif.

Application July 1, 1946, Serial No. 680,631

2 Claims. (Cl. 2—139)

2

This invention relates to improvements in the construction of shirts of the collar-attached type and is particularly directed to a method of making such shirts in a ready, facile, and rapid manner.

In the ordinary manner of making shirts, the collar is made out of a plurality of elements including outer or surface elements and an inner liner. These elements are ordinarily stitched together along the outer edges but not at the neckline and the assemblage is then turned inside out so as to produce a blind seam at the exposed outer edges. Subsequently this unfinished collar having a raw, neckline edge is attached to the shirt and during this step of attaching the collar it is necessary to carefully and accurately tuck or turn under the raw, unfinished edges of the various collar elements and attach them to the neckline edge of the shirt and/or shirt yoke. The last-described operation requires expert operators, is time-consuming, and an appreciable number of shirts made in this manner are imperfect, since the edges of the collar elements are often improperly or insufficiently tucked in, turned under, and stitched.

In accordance with the present invention, the method described hereinabove is discarded, and instead, a complete collar unit is separately formed, such collar unit being free from raw, unbound, or unfinished edges. These collar units may then be easily and rapidly attached to a shirt in the region of the neckline so that a complete collar-attached shirt is provided. Moreover, in accordance with the present invention, the collar units are provided with a distinctive, identifying edge marking which eliminates the necessity of attaching a separate label, trademark or other identification to the shirt.

It is an object of the present invention, therefore, to disclose and provide an improved method of making collar-attached shirts.

A further object of the invention is to disclose and provide a collar-attached shirt of an improved type wherein the collar is firmly, neatly, and positively attached to the body of the shirt.

A still further object of the invention is to disclose a complete collar unit provided with one edge carrying identifying marking.

In addition, it is an object of the invention to provide a complete collar unit free from raw, unfinished edges, which collar unit may be readily and simply attached to the body of a shirt by inexperienced operators.

These and other objects, advantages and adaptations of the invention will become appar-

ent to those skilled in the art from the following description of the method and construction of this invention. In order to facilitate understanding, reference will be had to the appended drawings, in which:

Fig. 1 is a plan view of a completed collar unit prior to attachment to a shirt.

Fig. 2 is a plan view of the upper portion of a shirt in extended form illustrating the method of attaching the collar unit to the shirt.

Fig. 3 is an enlarged transverse section taken along the plane III—III of Fig. 1.

Fig. 4 is an enlarged transverse section taken through the plane IV—IV of Fig. 2.

15 A complete collar unit made in accordance with the present invention is generally indicated at 10, and, as more specifically shown in Fig. 3, may consist of surface elements 11 and 12 and an inner liner element 13, these three elements being cut from suitable patterns and being substantially identical in shape and size. The complete collar unit may be said to be delineated by means of a back margin 14, point margins 15 and 16, and a neckline 17.

20 The collar unit is preferably made by first stitching the surface elements 11 and 12 (together with the inner or liner element 13 when such inner element is used) along the back margin 14 and the points 15 and 16 as indicated by 25 the line of stitching 18. The collar elements are in an inverted or wrong-side-out position at the time that the stitching 18 is applied to the points and back margin, no stitching being applied to the neck margin. The partially completed collar is 30 then turned inside out so as to place the surface elements 11 and 12 on the exterior, thereby giving rise to a blind seam along the points and back margin of the collar.

The raw unfinished edges of the inner and 35 outer surface elements, as well as the lining, in the region of the neckline, are then bound with a tape or other binding 20 by means of one or more lines of stitching, such as the line of stitching indicated at 21, thus giving rise to a complete collar unit, the neckline being enclosed by 40 the tape 20.

The tape 20 preferably carries an identifying 45 marking such as a trade-mark, name of manufacturer, or the like. In addition, the tape 20 may be of a distinctive color, the color of the tape indicating the quality or manufacturer. The tape 20 may also carry identifying marks denoting the size of the collar. It may be noted in passing that the collar unit shown in Fig. 1 is of the type 50 generally employed on sport or leisure shirts and

is normally folded or bent over itself along the dash line 22.

The collar unit described hereinabove may now be attached to a shirt. It is to be remembered that shirt constructions vary a great deal, since the shirts may be provided with a yoke, may be partially lined, etc. In the example illustrated in Figs. 2 and 4, the collar unit 10 is shown in combination with a sport type shirt including a yoke 24 and front part-linings 25 and 26, the front part of the shirt being indicated at 27. It will be evident to those skilled in the art that the complete collar unit, free from raw or unfinished edges, may be readily applied to the body of the shirt and stitched to the yoke 24, the front portions 27 and the part-lining 25 and 26 while these various elements are arranged in an inverted or wrong-side-out position, as for example, by means of a line of stitching indicated at 28. Upon being turned or transposed into final position, blind seams of attachment between the collar unit and the body of the shirt will exist.

The righthand portion of Fig. 2 shows the in-folded edge portions 27' and 26' of the front and part-lining portions of a shirt and similar in-folded portions are shown in Fig. 4. It is to be understood, however, that the line of stitching 28 is accomplished while the various parts are in an inverted or wrong-side-out position so that it is not necessary for the operator to carefully in-turn the edges prior to stitching. As previously indicated, the figures are simply exemplary of one form of shirt construction and the invention is not limited thereto. Moreover, although but one line of stitching 28 is shown as attaching the yoke and part-lining to the collar, two or three lines of stitching may be used, depending upon the strength desired. It is also to be noted that even though a part-lining is used, the band 20 is visible in the central portion of the neckline so that the marking carried by the band is utilizable in the complete shirt.

Those skilled in the art will appreciate the

great savings of time and labor which flow from this improved construction. Many variations and changes can be made from the specific construction described in detail. All changes coming within the scope of the appended claims are embraced thereby.

I claim:

1. An improvement in the construction of shirts of the collar-attached type comprising: a foldable collar unit free from stitching along its fold line characterized by absence of raw, unfinished edges and comprising a pair of virtually identical collar surface elements of equal width internally stitched together along the point and back margins of the collar to form blind seams, the raw edges delineating the marginal edge of the collar normally attachable to a shirt being bound and enclosed with a tape, said tape terminating at the point margin of the collar whereby said collar may be attached to a shirt through said bound edge.

2. In a method of making collar-attached shirts, the steps of: making a foldable, soft collar as a complete unit free from raw, unfinished edges by stitching surface elements of a collar along the points and back margin, turning the assembly inside out to produce blind seams at the margins of the points and back, binding the adjacent edges of the elements along the margin delineating the neckline, and finally attaching the collar to the neckline of a shirt body by stitching applied through said bound collar edge portion.

SAMUEL BURTON.
